DESIGN FOR A COMBINED FIREPLACE AND TRANSPARENT DOOR

Lucien Sulzer, Chicago, Ill.

Application November 23, 1933, Serial No. 49,831

Term of patent 3½ years

To all whom it may concern:

Be it known that I, LUCIEN SULZER, a citizen of the United States of America, residing at 432 West Superior Street, Chicago, county of Cook and State of Illinois, have invented a new, original, and ornamental Design for a Combined Fireplace and Transparent Door, of which the following is a specification, reference being had to the accompanying drawing, forming a part thereof.

Fig. 1 is a perspective view of the combined fireplace and transparent door, showing my new design; Fig. 2 is a detailed front view of the door. The dominant feature of the design resides in the transparent door.

I claim:

The ornamental design for a combined fireplace and transparent door, substantially as shown and described.

LUCIEN SULZER.
